UNITED STATES PATENT OFFICE

OSCAR W. NELSON, OF PORTLAND, OREGON

GRINDING MACHINE

Application filed November 6, 1930. Serial No. 493,879.

The invention relates to grinding machines, and has for its principal object the provision of a grinding machine adapted for extremely fine work, such for instance as 5 pointing pivots used in watches, clocks, and delicate instruments.

A further object of the invention is the provision of a portable grinding machine adapted to be supported in an operative position manually and to be connected to a driving shaft by means of an elastic belt to permit of operation of the machine in various positions, and adapt the grinding disk to be driven in either direction.

15 The invention will be described in detail hereinafter and will be found illustrated in the accompanying drawing, in which

Figure 1 is a view in elevation of the improved grinding machine showing it geared 20 to a driving shaft of a conventional motor,

Figure 2 is a longitudinal sectional view of the grinding machine, and

Figures 3 and 4 are transverse sectional views on planes indicated by the lines 3—3 25 and 4—4, respectively, of Figure 2.

In the drawing similar reference characters are used to designate corresponding parts throughout the several views.

As shown in the drawing the grinding machine comprises a handle 1 that is preferably enlarged at one end as shown at 2 to give stability to the machine and to eliminate vibration when in operation. Secured in the handle 1 that is preferably made of fibrous 30 material such as wood, or the like, is a bushing 3 of a suitable metal having longitudinal and pointed ribs or spines 4 that engage in the fibers of the handle to hold the bushing in position. Bushing 3 is provided with 35 a tubular bore 5 that extends from the smaller end of the handle 1 inwardly of the handle, but ends short of the inner end of the bushing, and the inner end of the bushing is provided with a reduced polygonal bore 6.

40 7 indicates a shaft or arbor inserted in the bore 5 and having a reduced and polygonal end 8 that engages in the bore 6, the angles of said reduced portion 8 being provided with threads 9 to receive a cap nut 10 to hold the shaft or arbor in position in the bushing, the bushing 3 ending short of the larger end of the handle 2 to provide for reception of the cap nut 10, as best shown in Figure 2.

The other end of the shaft or arbor 7 is provided with a flanged head 11. 12 indicates a sleeve mounted on the shaft or arbor 7 and rotatable on said shaft, said sleeve 12 being provided with a flange 13 engaging the flanged head 11, and the sleeve 12 is exteriorly threaded as shown at 14. 15 designates a grinding disk having a metal hub 16 that is splined as shown at 17 on the sleeve 12. A pulley 18 is also mounted on the sleeve 12 and is preferably formed with a hub 19 and flanges 20 and 21 secured thereto 50 in any suitable manner. The outer face of the flange 21 and the corresponding face of the hub 19 has a washer 22 of rubber or other friction material secured thereto by means of a circumferential outwardly directed returned flange 23 on said flange 21, that when in position as shown best in Figure 2 engages the hub 16 frictionally so that the grinding disk 15 is rotated simultaneously with the pulley 18. 24 designates a jam 55 nut mounted on the sleeve 12 to hold the pulley 18 in frictional engagement with the hub 16 as above stated.

25 designates a belt trained on pulley 18 and gearing the pulley to the shaft 26. In 60 Figure 1 the shaft 26 is shown as the driving shaft of a motor 27 but it will be apparent that any other source of power may be substituted for a motor shaft, and the arrangement shown in the drawing is for illustration only.

In use, the grinding machine being geared to a suitable shaft 26 is held in the hand and obviously is suitable for very delicate work 65

and particularly for finishing gear pivots in watches, clocks, and delicate instruments.

28 and 29 designate anti-friction bearings, bearing 28 being mounted in a recess 30 in the 5 flanged end of the sleeve 12, and bearing 29 being mounted between the end of the bushing 3 and the sleeve 12, said bearing being arranged to relieve the thrust on the ends of the sleeve 12.

10 What is claimed is:—

A portable grinding machine, comprising a shaft having a flanged head at one end, the other end of the shaft being reduced and polygonal in cross section, a handle having a 15 longitudinal bore therethrough, a sleeve secured in said bore and provided with a bore to receive the shaft, a threaded sleeve rotatably mounted on the shaft and having a flanged head engaging the head on the shaft, 20 a grinding disk splined on the threaded sleeve and abutting the head thereon, a pulley loosely mounted on the sleeve, a friction washer secured to the pulley and engaging the grinding disk, and a jam nut threaded on the threaded sleeve and engaging the pulley to hold it for 25 rotation with the grinding disk and threaded sleeve, said pulley being adapted to be geared to a motor shaft.

In testimony whereof I affix my signature.
OSCAR W. NELSON.
